US00D862730S

(12) **United States Design Patent** (10) Patent No.: **US D862,730 S**
 (45) Date of Patent: **** Oct. 8, 2019**

(54) **WHITE NOISE MACHINE**

(71) Applicant: **SHENZHEN QIANHAI PATUOXUN NETWORK AND TECHNOLOGY CO., LTD**, Shenzhen (CN)

(72) Inventor: **Zaihui Hu**, Shenzhen (CN)

(73) Assignee: **SHENZHEN QIANHAI PATUOXUN NETWORK AND TECHNOLOGY CO., LTD**, Shenzhen (CN)

(**) Term: **15 Years**

(21) Appl. No.: **29/697,202**

(22) Filed: **Jul. 5, 2019**

(51) LOC (12) Cl. **24-99**

(52) U.S. Cl. **USPC D24/231**

(58) **Field of Classification Search**

USPC D24/231, 188; D14/496, 215, 216, 168
 CPC A61F 11/08; A61M 21/00

See application file for complete search history.

Primary Examiner — Rhea Shields

(57) **CLAIM**

The ornamental design for a white noise machine, as shown and described.

DESCRIPTION

FIG. 1 is a perspective view of a white noise machine showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarge view of portion 9 shown in FIG. 2. The broken lines in the drawings depict portions of the white noise machine that form no part of the claimed design.

1 Claim, 9 Drawing Sheets
